Primary Examiner — Zenia Bennett

(74) *Attorney, Agent, or Firm* — Kenneth D. Baugh

(**) Term: **14 Years**

CLAIM

(21) Appl. No.: **29/373,425**

The ornamental design for a hair dryer heat shielding device, as shown and described.

(22) Filed: **Apr. 7, 2011**

DESCRIPTION

(51) **LOC (9) Cl.** 28-03

FIG. 1 is a perspective view of a hair dryer heat shielding device showing my new design

(52) **U.S. Cl.** D28/18

FIG. 2 is an exploded view of a hair dryer heat shielding device showing my new design.

(58) **Field of Classification Search** D28/12-19;

34/96-101; 392/380-385; 219/222; 2/174;

D2/865, 882, 893; D29/109, 110, 122

FIG. 3 is a side view of a hair dryer heat shielding device
